UNITED STATES PATENT OFFICE

166,844

TRAILER

Charles H. Becker, Ironwood, Mich., assignor to Ironwood Trailer Coaches, Inc., Ironwood,
 Mich., a corporation of Michigan

Application June 28, 1950, Serial No. 10,822

Term of patent 3½ years

(Cl. D14—3)

To all whom it may concern:

Be it known that I, Charles H. Becker, a citizen of the United States, residing at Ironwood, State of Michigan, have invented a new, original, and ornamental Design for a Trailer, of which the following is a specification, reference being had to the accompanying drawing, forming a part hereof.

Figure 1 is an exterior view in perspective of a trailer embodying my new design; Figure 2 is an interior view of a trailer embodying my new design with the folding partition sections partially closed; Figure 3 is a view like Figure 2 but showing the folding partition sections in a fully opened position; and, Figure 4 is a view like Figure 3 with the table in the extended position.

The characteristic features of my design reside in the interior portions of the trailer shown in Figures 2, 3 and 4 of the drawing.

I claim:

The ornamental design for a trailer, as shown and described.

CHARLES H. BECKER.
